Primary Examiner — Darlington Ly*Assistant Examiner* — Jeremy Koenig(74) *Attorney, Agent, or Firm* — BROOKS KUSHMAN
P.C.(57) **CLAIM**

The ornamental design for a rim as shown and described.

DESCRIPTION

FIG. 1 is a front perspective view thereof;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a rear perspective view thereof.

The broken lines depict portions of the rim that form no part of the claimed design.

1 Claim, 8 Drawing Sheets# US D1,096,576 S
